UNITED STATES PATENT OFFICE.

WILLIAM C. WHITEHEAD AND ABRAM L. TEETOR, OF INDIANAPOLIS, INDIANA; SAID TEETOR ASSIGNOR TO JOHN H. LATSHAW, OF SAME PLACE.

SAND-MOLDING MACHINE.

SPECIFICATION forming part of Letters Patent No. 364,388, dated June 7, 1887.

Application filed March 21, 1887. Serial No. 231,767. (No model.)

To all whom it may concern:

Be it known that we, WILLIAM C. WHITEHEAD and ABRAM L. TEETOR, of Indianapolis, county of Marion, and State of Indiana, have invented certain new and useful Improvements in Sand-Molding Machines; and we do hereby declare that the following is a full, clear, and exact description thereof, reference being had to the accompanying drawings, in which like letters refer to like parts.

Our invention relates to the construction of sand-molding machines, and is an improvement upon the machine shown and described in the application of J. and J. H. Latshaw, filed January 10, 1887, Serial No. 223,848, and in the earlier patent issued to John Latshaw, August 28, 1883, No. 283,905, and will be understood from the following description.

In the drawings, Figure 1 represents an interior side view of our improved machine, the full lines indicating the position of the parts when the pattern-plate is raised, and the dotted lines indicating the position of the movable parts of the mechanism when the pattern-plate is lowered, the frame-work and shaft being in cross-section. Fig. 2 is an interior end view of the same, the frame-work and pattern-plate being in cross-section on the line xx , Fig. 1. Fig. 3 is a detailed view of the triangular piece to which the short arm or link a' is pivoted.

The frame-work of the machine and many of its features are substantially the same as shown in the application of J. and J. H. Latshaw before referred to, the differences which constitute our improvements being in the means for sustaining the guides and in pivoting the lower ends of the jointed levers to the hangers that support the guides in which the slides of the pattern-plate move, a different means for connecting the arms of the rock-shaft to the jointed levers, and a provision for counter-balancing the weight of the pattern-plate and patterns by springs coiled upon the ends of the shaft, as hereinafter more fully described.

The frame-work of the machine consists of a base, b' , mounted on rollers r , and the top piece, t , upon which the parting-plate p rests, these upper and lower parts being connected by uprights u , as shown in Fig. 1. Between these uprights and near each end are curved braces

or hangers h h' , which are bolted to the top, the lower ends of each pair meeting and being connected together, and furnishing a pivotal support for the lower ends of the jointed levers j j' , as shown in Figs. 1 and 2. These hangers have projections or guides g , which are channeled to receive the slides s' , connected to the under side of the pattern-plate, which move freely in such channels when the pattern-plate is being raised or lowered. The upper ends of the jointed levers are pivoted at 55 to projections on the under side of the pattern-plate p' , as shown in Fig. 1, their lower ends being pivoted at 66 in the lower united ends of the 65 hangers h h' . Thus the pattern-plate and the mechanism connected therewith—namely, the jointed levers and the guides—are supported directly, by means of the curved hangers h h' , between the ends, and free from contact with 70 the other parts of the frame, and the object of this is to prevent the jointed levers at their lower pivotal connection from being thrown out of line when the pattern-plate is lowered, there being a tendency so to force them out of 75 line when they are pivoted to bars uniting cross-pieces at the ends of the frame, as shown in the construction in the former application hereinbefore referred to.

It has been found after careful experiment 80 that in drawing the pattern from the sand the two ends of the pattern-plate do not descend equally, and that there is more or less difference in the level of the ends at such times, and in order to remedy this we have devised the 85 peculiar method of pivoting the shorter arm or link which connects the arm of the rock-shaft to the jointed levers herein shown, namely: this shorter arm or link a' is pivoted at one end, at 2, to the arm a . Its other end, 90 instead of being pivoted at the central point, 4, of the jointed lever j , as is the case upon the other side of the machine, is pivoted at 7 to one corner of a spherical triangle, S , all the sides and angles of which are unequal, and the 95 upper corner of this triangle is connected at 4 with the jointed lever j , and when in that position the vertical side of this triangle becomes the lower half of the jointed lever on that side, so that the distances from 4 to 5 and 100 from 4 to 6 are equal. The angles of this triangle have the following values: the angle A

B C is fifty-seven and one-half degrees, the angle B A C is forty-six degrees, the angle A C B is seventy-six and one-half degrees. These angles having a fixed value, insure the relative proportional lengths of the sides, and a mathematical calculation establishes the fact that these elements are necessary in order to effect the result desired—namely, the movement of the pattern-plate in either direction, so that its upper surface is always in a horizontal plane. This construction, when the parts are in the position shown in the full lines, makes the angle 672 equal to the angle 136, and when the pattern-plate is lowered and the parts are in the position shown in the dotted lines in Fig. 1 the angles of the jointed levers on both sides are equal, indicating that the surface of the pattern-plate is level.

Our improvement further consists in attaching the coiled springs *sp* at one end to the shaft *s*, coiling them around the shaft, and connecting the other end of the spring with the brackets *b b'*, in which the shaft is journaled. The object of this is to use the force of the springs against the weight of the pattern-plate and patterns, so that it will act as a sort of counterbalance and prevent any jerking or unsteady movement of the pattern-plate and its load at any point of its movement, and it accomplishes this by throwing the force of the spring against the rotary movement of the shaft as the pattern-plate descends. This force being exerted equally and constantly, prevents any sudden or irregular movement of the pattern-plate while being lowered.

It must be understood that the working parts of the machine are practically supported by the pairs of hangers *h h* and *h' h'* on each end, and are not only held free from contact with the ends and base of the frame, but also above the floor, so that no jar of the frame or unevenness of the floor will seriously disturb the relation of the working parts or the operation of the machine.

What we claim as our invention, and desire to secure by Letters Patent, is the following, viz:

1. A sand-molding machine wherein the pattern-plate is supported upon a pair of jointed levers at each end and connected by links of unequal length to a rock-shaft supported in brackets connected with the frame, which is revoluble in its bearings, so as to operate the jointed levers connected therewith and raise or lower the pattern-plate, the shorter link pivoted at one end to an arm connected with such rock-shaft and at the other to a projection from the jointed levers on that side of such length and angle as to maintain the pattern-plate in a level position throughout its entire length at all points of its movement, substantially as shown and described.

2. A sand-molding machine comprising in combination a frame-work, a parting-plate on top, a rock-shaft journaled in brackets connected with such frame, arms on the rock-shaft pivoted to links of unequal lengths which

connect such arms to a pair of toggle-levers hinged at their upper ends to the pattern-plate and at their lower ends to curved hangers or braces bolted to the top of the frame and hanging down free between the ends of the frame, such hangers having channeled guides to admit the movement therein of slides fastened to and beneath the pattern-plate, where-by the pattern-plate and its load is suspended beneath the frame-work and free from other contact therewith in its ascent or descent, and one or more springs coiled upon the shaft, and connected also to the brackets in which such shaft is journaled, whose force evenly resists the rotation of such shaft, substantially as shown and described.

3. A sand-molding machine comprising in combination a frame-work, a parting-plate supported thereon, an armed shaft revoluble in bearings connected with the frame, and the pattern-plate supported upon toggle-levers at each end and upon slides moving in guides formed upon braces hanging from the upper part of the frame and between the ends thereof, whose united lower ends provide pivotal support for the lower ends of the toggle-levers, one set of such toggle-levers being connected to one arm of the rock-shaft by a link and the other set being connected by a triangular frame whose sides are unequal and whose angles have the values hereinbefore given to a shorter link which is pivotally connected to the other arm of the rock-shaft at a point diametrically opposite the arm connected to the longer link, substantially as shown and described.

4. A sand-molding machine comprising in combination a frame-work, a parting-plate supported thereon, an armed shaft revoluble in bearings connected with the frame, and a pattern-plate supported upon toggle-levers at each end and upon slides moving in guides formed upon braces hanging from the upper part of the frame, and between the ends thereof, whose united lower ends provide pivotal support for the lower ends of the toggle-levers, one set of such toggle-levers being connected to an arm of the rock-shaft by a link and the other set being connected by a triangular frame whose sides are unequal and whose angles have the values hereinbefore given to a shorter link which is pivotally connected to the other arm of the rock-shaft at a point diametrically opposite the arm connected to the longer link, and one or more springs connected to the shaft and frame whose force evenly resists the rotation of the rock-shaft when the pattern-plate is being lowered, substantially as shown and described.

In witness whereof we have hereunto set our hands this 17th day of March, 1887.
